CLAIM

The ornamental design for a keyboard for a handheld device as shown and described.

DESCRIPTION

FIG. 1 is a front left perspective view of an embodiment of a keyboard for a handheld device;

FIG. 2 is a rear right perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a top view thereof, shown mounted in a handheld device; and,

FIG. 10 is a top view of another embodiment of a keyboard for a handheld device.

The broken lines depict portions of the keyboard for a handheld device that form no part of the claimed design.
